CLAIM

The ornamental design for a modular wall mount for a vehicle, as shown and described.

DESCRIPTION

FIG. 1 is a front perspective view of a modular wall mount for a vehicle in accordance with my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken lines depict portions of the mount that form no part of the claimed design.

1 Claim, 5 Drawing Sheets# US D1,099,575 S
